UNITED STATES PATENT OFFICE.

RALPH N. DOBLE, OF BAYSIDE, NEW YORK, ASSIGNOR, BY MESNE ASSIGNMENTS, TO STATE STREET TRUST COMPANY, TRUSTEE, OF BOSTON, MASSACHUSETTS, A CORPORATION OF MASSACHUSETTS.

CONTAINER.

Application filed December 10, 1921. Serial No. 521,507.

This invention relates to packaging containers, and particularly to sealed containers which are capable of simple and cheap construction, but are durable and capable 5 of extended use.

In the packaging of cake and other food or perishable products, it is desirable to provide a sealed package in which to place the product on the market, but this package 10 should permit of easy access to the contents without losing its efficiency as a container and being no longer of further use.

To this end therefore I provide a package which may be cheaply, quickly and efficiently formed, filled and closed. In this package I use a form of seal which may be destroyed without affecting the package as a whole or destroying its usefulness as a container. I also provide a means of detecting 20 the line of seal of the package when it is provided with a wrapper.

The construction and method of folding my container is described and illustrated in the accompanying specification and drawings, throughout which like reference characters are employed to indicate corresponding parts. In the drawings:

Fig. 1 is a view of the carton blank, with the lines of fold indicated.

Figs. 2 and 3 are diagrammatic views showing the different steps in the folding process.

Fig. 4 is a perspective view of the sealed pack with the wrapper torn away and the seal broken by the insertion of a knife blade, and

Fig. 5 is a section on the line 5—5, Fig. 4.

The carton blank, formed of cardboard or other inexpensive stock, is adapted to be 40 folded longitudinally to provide a top panel 1, side panels 2 and 3, a bottom panel 4, a sealing flap 5, preferably integral with the top panel 1, and a second sealing flap 6, preferably integral with the side panel 3. The sealing flaps 5 and 6 are adapted 45 to be turned inwardly into the box and fastened together to form a seal joint, movable independently of the container walls and which seal may be destroyed without mutilating the container itself.

The blank is also folded transversely to form the end flaps 7, 8, 9 and 10, adapted

to be overlapped when the box is folded into shape, the flaps 7 being preferably cut on an arc, so that the top panel 1 may be 55 opened and closed freely after the seal is broken and the package opened.

It is of course desirable that the carton be formed with the least possible loss of time, and this is accomplished by the folding and sealing machine in which my package may be formed.

Referring to Fig. 2, the sealing flaps 5 and 6 are first turned; second, the front 2 and the side panel 3; third, the flaps 5 and 6 are brought together and gummed or otherwise permanently fastened so that in themselves, independent of any panel of the box, they form a complete seal. This partially folded blank is then placed in a bottoming machine which overlaps and unites the end flaps 7, 8, 9 and 10, as shown in Fig. 3. First, the curved flap 7 is folded; second, the flap 10; third, the flap 9, and lastly, the flap 8 to which has been applied 75 some adhesive substance is folded into position. The content is then deposited in the partially completed carton, which is placed end for end in the topclosing machine, and the end flaps 11, 12, 13 and 14 are overlapped in the same fashion as the flaps 7, 8, 9 and 10. The foregoing series of operations produces a completely closed, filled package 15, ready to be wrapped.

This package is then covered by any suitable wrapper W but I provide a wrapper with means for indicating the line of seal of the carton which it covers, as the dotted line 16 shown in Fig. 4.

To open this package, a knife blade or other sharp instrument B is inserted through the indicating line 16 on the wrapper W between the sealed portions 5 and 6, thereby breaking the seal so that the panel 1 may be lifted up, withdrawing the flaps 90 7 and 11 from the end portions without mutilating or destroying the package as a container capable of further use.

To reclose the box, the panels 7 and 11 are 100 inserted in the position they formerly occupied in the end portions, and the panel 1 is pressed into position, so that all the parts of the box meet to form a complete, closed box.

Various modifications in the form and construction of my device may obviously be resorted to without departing from the spirit of my invention, if within the limits of the appended claims.

What I therefore claim and desire to secure by Letters Patent is:

1. A rigid non-collapsible top-opening carton, comprising top, bottom and side panels, said bottom and side panels having overlapping closure flaps adapted to be sealed to each other to form a rigid end-closed container, and said top panel having arcuately curved end flaps adapted to swing freely into and out of the container past said end-closure flaps when the top panel is opened and closed, and having an inturned longitudinally extending sealing flap at its free edge, and one of said side panels having a similarly disposed sealing flap adapted to abut said sealing flap of the top panel when the container is closed and to be adhesively united thereto whereby to provide a rupturable seal internally of the package permitting delivery of package contents

through the top of the container when the top panel is swung open.

2. A rigid non-collapsible top-opening carton, comprising a blank having foldable top, bottom and side panels, said bottom and side panels having overlapping closure flaps adapted to be sealed to each other to form a rigid end-closed container, and said top panel having arcuately curved end flaps adapted to swing freely into and out of the container past said end-closure flaps when the top panel is opened and closed, and having an inturned longitudinally extending sealing flap at its free edge, and one of said side panels having a similarly disposed sealing flap adapted to abut said sealing flap of the top panel when the container is closed and to be adhesively united thereto whereby to provide a rupturable seal internally of the package permitting delivery of package contents through the top of the container when the top panel is swung open.

In testimony whereof I affix my signature,

RALPH N. DOBLE.
